DRILLING APPARATUS

Win W. Page, Michigan City, Ind., assignor to
 Joy Manufacturing Company, a corporation of
 Pennsylvania

Application March 10, 1944, Serial No. 525,869

24 Claims. (Cl. 255—47)

1

This invention relates to drilling apparatus, and more particularly to improvements in feed control means for drilling apparatus of the rotary type.

In drilling hard material, such as rock, by rotating a bit impregnated with diamonds or borts while it is in engagement with the material to be drilled, and feeding the bit toward the work as the material is cut away, there may be, if the bit is fed too rapidly, a binding of the bit, resulting in an overloading of the bit rotating motor, a burning of the bit or a fracture of some part of the drilling apparatus. Some of these difficulties may be encountered, regardless of the type of bit, if excessive feeding pressures are used. By controlling automatically the rate of feed in accordance with the resistance to rotation of the drill bit, it is possible to prevent the undesirable results above mentioned from occurring, and at the same time to maintain the feeding pressure that is necessary to obtain the fastest drilling speed.

The invention from one aspect may comprise a drill feeding means embodying relatively rotatable, mechanically interengaged feeding elements for effecting feed of a drilling implement, together with means for automatically controlling the relative rotation of the feeding elements in accordance with the resistance to rotation of the drilling implement, to regulate the rate of feed. Desirably, the invention may comprise a drill feeding means including a torque motor for providing a feed-effecting force, and means automatically controlled by load changes on the drilling implement to control the transmission of the force provided by the torque motor to effect a feeding of the drilling implement. The feeding means may comprise relatively rotatable feed screw and nut elements and a friction device, controlled by the load changes on the drilling implement, for automatically controlling the relative rotation of the feeding elements. The friction device may desirably be in the form of a brake and may control rotation of either the feed screw or the feed nut. In a preferred embodiment the brake may be applied to resist rotation of the element driven by the torque motor, thereby reducing the relative rotation between the feed elements and decreasing the rate of feed. Again, the brake may be normally applied to hold one of the feed elements against rotation while the other element is rotated by the torque motor, and, on overloading of the drilling implement, the brake may be automatically released so that the normally braked element may rotate, thereby re-

2

ducing the relative rotation between the elements and decreasing the rate of feed. While reaction of the motor casing is a preferred source of feed controlling force, it will be understood that relative rotation between parts in the drive of the bit, or variations in the power demand of an electric bit-rotating motor, may be caused to effect feed control without departing from my invention in its broader aspects. In different embodiments of the invention, the motor for rotating the drilling implement, as well as the torque motor, may be caused either to move along a guide member with the drilling implement during feeding, of the latter or may be held stationary while the drilling implement is fed relative to its work.

It is therefore an object of this invention to provide an improved drilling apparatus having improved feed control means embodied therein. Another object is to provide in a rotary type drilling apparatus an improved feed control means operative to control the feeding of the drill bit in accordance with the resistance to rotation of the bit. Still another object is to provide an improved feed control means for a rotary type drilling apparatus, said feed control means operative in accordance with the load on the bit rotating motor for varying automatically the drill feed. Another object is to provide relatively rotatable feeding elements for a bit rotating motor, and feed control means operatively connected with the bit rotating motor and actuated thereby as the load on the motor changes for altering the resistance to rotation of one of said elements. Still another object is to provide improved feeding means for a drilling implement of the rotary type, said feeding means including relatively rotatable feeding elements operative on relative rotation to effect feed, and means responsive to the resistances to rotation of said drilling implement for controlling the relative rotation between said feeding elements. Yet another object is to provide relatively rotatable feeding elements for a drilling implement of the rotary type, and means for controlling the relative rotation between said elements, said controlling means including means for resisting the rotation of one of said feeding elements whereby the rate of relative rotation between said elements is reduced, and means for actuating the resisting means to resist the rotation of the feeding element when the resistance to rotation of the drilling implement exceeds a predetermined amount. Another object is to provide relatively rotatable feeding elements for a drilling implement of the rotary type, with controlling means

for one of the same normally coacting with it so that the maximum speed of relative rotation is secured, but operative at a predetermined maximum load for changing the control so as to result in a reduction in the rate of relative rotation. Other objects and advantages of the invention will, however, hereinafter more fully appear.

The present application is a continuation-in-part of my copending application Serial No. 10 368,692, filed December 5, 1940, now abandoned.

In the accompanying drawings there are shown for purposes of illustration several forms which the invention may assume in practice.

In these drawings,

Fig. 1 is a plan view of a drill mechanism having incorporated therein one illustrative embodiment of the invention.

Fig. 2 is a side elevational view, with parts broken away, of the drill mechanism shown in Fig. 1.

Figs. 3 and 4 taken together constitute an enlarged view in longitudinal vertical section through the drill mechanism shown in Figs. 1 and 2.

Fig. 5 is a transverse sectional view through the drill mechanism and taken on the plane of the line 5—5 of Fig. 3.

Fig. 6 is a detail sectional view taken on the line 6—6 of Fig. 3.

Fig. 7 is a transverse sectional view taken on the line 7—7 of Fig. 4.

Fig. 8 is a transverse sectional view taken substantially on the line 8—8 of Fig. 3.

Fig. 9 is a fragmentary sectional view taken on a plane corresponding to the plane of Fig. 3, and showing a modification of the invention.

Fig. 10 is a cross sectional view taken substantially on the plane of the line 10—10 of Fig. 9.

Fig. 11 is a longitudinal sectional view showing another modification of the invention.

Fig. 12 is a cross sectional view taken substantially on the plane of the line 12—12 of Fig. 11.

Fig. 13 is a side elevational view of a drilling apparatus, with parts shown in longitudinal section, having still another modification of the invention embodied therein.

Fig. 14 is a cross sectional view taken substantially on line 14—14 of Fig. 13.

Fig. 15 is a longitudinal sectional view showing the rear portion of the feeding means for the drilling apparatus shown in Fig. 13.

Fig. 16 is a cross sectional view taken substantially on line 16—16 of Fig. 13.

In the illustrative embodiment of the invention shown in Figs. 1 to 8 inclusive, a rotary type drilling apparatus generally designated 1 is mounted on a supporting and guiding structure, generally designated 2, and has associated therewith drill feeding means generally designated 3 and feed control means generally designated 4.

The drilling apparatus 1 includes a bit rotating motor 6 carried by a rear head member 7 which is slidably guided on the supporting and guiding structure 2 in a manner that will shortly be described. The motor is herein of the high speed electric type and includes a casing 8 provided with front and rear heads 9 and 10 held in assembled relation with respect to the casing by usual tie bolts 11. The motor has a usual field 13 and an armature rotor 14, the latter having a shaft 15 which is journaled in bearings 16, 16 suitably supported in the motor heads. Attached to the forward end of the shaft 15 is a chuck 18 for receiving the shank of a hollow drill rod 19

which carries a drill bit 20. The rear motor head 10 has a rearward cylindric projection 22 mounted for limited rotation in ball bearings 23 supported within a bore 24 formed in the head member 7. The bearings 23 are retained in the bore 24 by means of a retaining ring 25 secured, as by screws 26, to the head member 7; and the cylindric projection is held against axial displacement with respect to its bearings by means of an end plate 27 secured, as by screws, to the projection 22.

Extending through a bore in the shaft 15 is a liquid conducting tube 28 which is threaded at its rear end within a member 29 secured to the rear head member 7, and cleansing liquid is supplied through a passage 30 in the member 29 to the tube 28 where it is conducted to the hollow drill rod and through the latter to the drill hole. Attached to the rear end of the shaft 15 is a member 32 fitting closely around the tube 28 and having an annular flange engaging an annular flange on the end plate 27 to provide a seal preventing any cleansing liquid escaping around the end of the tube 28 from passing to the bearings 16 in the rear motor head and to the motor windings. A passage 33 in the member 29

connects the space surrounding the rear end of the tube to a vent passage 34 so that any liquid escaping around the end of the tube may drain away. The structure so far described, except for the rear head member 7, is similar to that disclosed in a copending application to one Carl E. Dittmer, Serial No. 328,737, now matured into Patent No. 2,296,273, patented September 22, 1942, and further description of the same herein is accordingly unnecessary. The rear head member 7 is provided with a depending portion 36 that projects within a trough-like member 37 of the supporting and guiding structure 2, as shown in Figs. 3 and 5. Formed on the sides of the depending portion are flanges 39, 39 which are slidably received in grooves 40, 40 in the sides of the member 37 for guiding the drilling apparatus as it moves along the supporting and guiding means.

Referring to the drill feeding means, it will be noted that there is provided a feed screw 42 extending longitudinally through the trough-like member 37 in parallelism to the grooves 40, and the feed screw is journaled at its forward end in a plate 43 extending transversely of the member 37 and at its rearward end in a housing 44, as shown in Figs. 3 and 4. The plate 43 and the housing 44 are held in fixed positions to the ends of the member 37 by tie rods 46. Keyed to the feed screw at its rearward end is a worm wheel 47 meshing with a worm gear 48 that is keyed to a shaft 49 extending transversely through the housing 44 and journaled in the sides of the housing as shown in Fig. 7. Attached to a side of the housing, as by screws 50, and in alinement with the shaft 49 is a motor 51, shown herein as an electric torque motor, having its rotor attached to an end of the shaft 49 projecting through the side of the housing. A switch box 52 is attached, as by screws 53, to the rear end of the housing 44 and contains a switch having a control handle 54 for controlling the flow of electric current through lines 55 and 56 to the motors 6 and 51, respectively. The feed screw extends, as shown in Fig. 3, through the depending portion 36 of the head member 7, and a feed nut 58 having a head 59 engaging surfaces on the head member 7 is clamped firmly to the head member in threaded engagement with the feed screw by a clamping nut 60. As the feed nut is held against bodily

70 and rotative movements relative to the head mem- 75

ber 7 there will be, during rotation of the feed screw by the motor 51 through the worm gear 48 and the worm wheel 47, a feeding or a retractive movement of the drilling apparatus relative to the supporting and guiding structure 2. Formed on the member 37 of the supporting and guiding structure is a swivel plate 62 adapted for clamping in the saddle mounting of a conventional rock drill support. With the drilling apparatus supported at the face of material to be drilled and a rotation of the feed screw in a direction to effect movement of the drilling apparatus toward the material, there will be, on engagement of the material by the drill bit and on rotation of the drill bit by the motor 6, a drilling of the material. If the drill bit is unable to cut its way as rapidly as the drilling apparatus is fed toward the material there will be a binding of the bit with a resulting increase in the load on the bit rotating motor, and if the load is increased sufficiently the bit rotating motor may be stalled or the bit may be damaged. To prevent stalling of the motor or damage to the bit, there is provided the feed control means generally designated 4.

The feed control means 4, as shown in Fig. 3, includes a sleeve 64 surrounding the feed screw and having splines 65 slidably fitting within grooves 66 formed in the feed screw, as shown in Fig. 8, so that the sleeve is held against rotation relative to the feed screw but is permitted to move longitudinally thereof. The sleeve 64 is rotatably supported at its front and rear ends, respectively, within an opening in the front wall of a recessed member 68 which is attached to the head member 7, as by screws 69, and within an opening in a cover plate 70 attached to the recessed member, as by screws 71. The sleeve is held against bodily movement relative to the head member and longitudinally of the feed screw by split rings 72, 72 engaging the recessed member 68 and the cover plate 70. Held to the sleeve 64 are friction elements in the form of brake disks 73 interleaved with other friction elements in the form of brake disks 74 held within the recessed member 68 against rotation relative to the latter in any suitable manner. Surrounding the feed screw is a shipper ring 75 having projecting members 76 extending through openings in the front wall of the recessed member 68 into engagement with one of the brake disks. Formed in the head member 7 is a chamber 77, and extending through this chamber transversely of the drilling apparatus is a rod 78 having its ends supported by the side walls of the chamber, as shown in Fig. 5. A shipper arm 79 is pivotally supported at one of its ends by the rod 78 and at its other end is provided with forked arms 80 having projecting portions 81 fitting within an annular groove 82 in the shipper ring 75. The shipper arm is provided between its ends with an elbow-like bend 84, and fixed to the end plate 27 of the drill rotating motor is a cam device 85 having a cam surface 86 for engaging the elbow 84 and forcing the shipper arm to swing about its pivot and effect a pressing together of the brake disks through the shipper ring when the drill rotating motor is caused to rotate in the bearings 23 in a counter-clockwise direction as viewed in Fig. 5. Threaded into an opening in the end plate 27 is a pin 88 having its outer end projecting a short distance from the rear surface of the plate, and a plunger 89 is reciprocable within a sleeve-shaped member 90 which is threaded into an opening in a side of the head member 7, and the plunger is forced by a spring 91 against the side of the pro-

jecting portion of the pin 88. The force of the spring 91 is such that it prevents the motor field 13 and casing 8 from turning in the bearings 23 in a counter-clockwise direction as viewed in Fig. 5, during normal drilling operations, but on increase of the motor load above a safe limit the motor casing turns against the force of spring 91 and causes the cam device 85 to swing the shipper arm 79 about its pivot and effect an application of the brake disks, slowing down or stopping the drill feed.

The mode of operation is as follows: The swivel plate 62 of the supporting and guiding means is clamped in the saddle mounting of a drill support 15 at the face of the work and the switch control handle 54 is operated to close the switch and supply current to the drill rotating motor 6 and to the drill feeding motor 51. The motor 51 is run in a direction to cause the feed screw 42 to be driven through the worm gear 48 and the worm wheel 47 in such a way that the drilling apparatus will be fed toward the work due to the engagement of the non-rotatable feed nut 58 with the feed screw. As the drill bit is moved into engagement with the work, drilling will take place, and if the load on the drill rotating motor is not too great the body of the motor will be held against rotation in the bearings 23 by the spring 91 forcing the plunger 89 against the pin 88. If the feeding pressure is 20 such that the drill bit 20 is unable to cut its way without increasing abnormally the load on the bit rotating motor, there will be a turning of the motor in the bearings 23 against the force of spring 91, and the cam device 85 will effect a 25 swinging of the shipper arm 79 in a direction to cause the brake disks 73 and 74 to be pressed together and slow down or stop the rotation of the feed screw in a feeding direction.

There is shown in Figs. 9 and 10 a modification 30 of the invention in which a feed nut 95 is rotatably supported at its front end by a bearing 96 carried by a depending portion 97 of the head member 7, and rotatably supported at its rear end by a bearing 98 carried by the cover plate 70. The feed nut 95 threadedly engages a feed screw 100, and surrounding the feed nut are friction elements 101 held against rotation relative to the nut and interleaved with friction elements 102 which are held within the recessed member 68 35 against rotation relative to the latter, in any suitable manner. A shipper ring 103 surrounds the feed nut and has fingers 104 projecting through openings in the member 68 into engagement with the friction disks. A spring 105 surrounding the feed nut acts between the depending portion 97 and the shipper ring to urge the latter in a direction to press the friction elements into engagement with each other. Pivotally supported within the chamber 77 on a rod 106 is an arm 107 having forked portions 108 which carry projecting portions 109 extending into an annular groove 110 in the ring 103. The arm 107 extends above its pivotal supporting rod, and the upper portion of the arm is engageable by the cam device 85 and caused to swing in a clock-wise direction by the latter when the drill rotating motor is overloaded. It will be seen that the feed nut will be held against rotation by the friction elements during normal drilling, but, as the drilling loads become excessive, the arm 107 will be swung in a direction to force the shipper ring out of engagement with the friction elements so that the braking force is removed, or at least decreased, and the feed nut rotates with the feed screw, decreasing or stopping the feed.

In Figs. 11 and 12 there is shown a modification in which a feed screw 115 is supported by a guide member 116 and held against rotation relative to the latter. Slidably mounted on the guide member 116 is a head member, generally designated 117, to which the drill rotating motor 6 is operatively connected, as described in the first form of the invention. The head member 117 has a depending section 118 rotatably supporting a feed nut 119 in threaded engagement with the feed screw 115. The feed nut is provided with teeth 120 which mesh with the teeth of a worm gear 121 keyed to a shaft 122 supported by and extending transversely of the head member 117. Fixed to the shaft 122 is a gear 123 meshing with a gear 124 fixed to a shaft 125 supported by the head member. Also connected to the shaft 125 is a bevel gear 127 meshing with a bevel gear 128 fixed to one end of the power shaft 129 of a motor 130 secured, as by bolts 131, within a chamber 132 in the head member 117. Surrounding the power shaft 129 adjacent its other end are friction elements 134 held against rotation relative to the power shaft and interleaved with friction elements 135 which are held against rotation relative to the head member. A plate member 136 is provided with projecting portions 137 which are adapted to press the friction elements together when the plate member is moved in a rearward direction. A lever 138 pivotally supported at 139 is adapted to be swung by the cam device 85 to apply pressure to the plate 136 to force the plate member in a direction to press the friction elements together when the drill rotating motor is overloaded. During normal drill loads, the motor 130 operates to drive the feed nut 119 through the bevel gears 128, 127, the shaft 125, the gears 124, 123, the shaft 122, the worm gear 121, and the teeth 120 on the feed nut. When the drill rotating motor becomes overloaded, it rotates slightly relative to the head member 117 and causes the cam device 85 to act on the lever 138 to force the plate member 136 in a direction to press the friction elements together. The rotation of the power shaft 129 is then resisted and caused to slow down, thereby reducing the rate of rotation of the feed nut.

In Figs. 13 to 16 there is shown another modification in which a supporting and guiding member 140 is shown on which a head member 141 is supported and held in a fixed position, as by bolts 142. Operatively connected to the head member in a manner similar to that described in the first form of the invention, but projecting rearwardly from the head member, is a drill rotating motor 6. In this case, a shaft 144 extends through the head member 141 and axially through the rotor of the drill motor. Grooves 145 formed in the shaft are adapted to receive keys fixed to the rotor so that the shaft will be caused to rotate with the rotor but may move axially relative to the rotor. As in the first form of the invention, a feed screw 146 is rotatably supported by the member 140 and is caused to be rotated through a worm wheel 47 keyed to the feed screw and meshing with a worm gear 48 which is fixed to a shaft 49 driven by a motor 51. A switch 52 having a manually operated lever 54 is adapted to control the supply of current to the motors 6 and 51.

Surrounding the feed screw is a sleeve-shaped member 150 having spines fitting within grooves 151 in the feed screw so that the sleeve member must turn if the screw turns. The sleeve member is rotatably supported at one end in the wall of a recessed member 152 attached to a depend-

ing portion 153 of the head member 141, and is rotatably supported at its other end in a cover plate 154 attached to the recessed member, as by screws 155. Held to the sleeve member are friction elements 156 interleaved with friction elements 157 held within the recessed member against rotation relative to the latter. A shipper ring 158 is provided with projecting portions extending through openings in the recessed member for pressing the friction elements together, and an arm 160 is pivotally supported by the head member 141 and is adapted to be swung by the cam device 85 in a direction to move the shipper ring toward the friction elements.

A feed nut 162 threadedly engages the feed screw at the forward side of the head member 141 and is clamped within an opening in a drill feed member 163 which is provided, as shown in Fig. 16, with guide flanges 165 slidably received in guideways 166 in the member 140. The member 163 is provided in its upper portion with a recess which contains a bearing 167 rotatably supporting the shaft 144 and adapted to exert rearward feeding forces on the shaft 144, and a thrust bearing 168 which acts against a collar 170 threaded on the shaft for forcing the latter in a forward feeding direction. Carried by the shaft 144 is a chuck 171 adapted to receive a drill rod 172 which has fixed to its outer end a drill bit 173.

As the feed screw is rotated by the motor 51, the feed nut moves along the feed screw and causes the drill rod to be fed by reason of its connection to the feed member 163. If the load on the drill rotating motor becomes too great, the motor rotates relative to the support member 141 and actuates the arm 160 through the cam device 85, pressing the friction elements together and resisting rotation of the feed screw.

As a result of this invention there is provided an improved feed control means for a rotary type drilling apparatus. It will be noted that as a result of the improved feed control means the rate of drill feed may be gradually reduced until the feeding of the bit is completely stopped, when the load on the bit rotating motor increases beyond a safe limit. By means of the improved feed control means there is obtained protection for the drilling apparatus and an automatic regulation of the feeding pressure, so that there may be a drilling of the material at a maximum safe rate. Other advantages of the invention will be clearly apparent to those skilled in the art.

While there are in this application specifically described several forms which the invention may assume in practice, it will be understood that these forms of the same are shown for purposes of illustration and that the invention may be further modified and embodied in various other forms without departing from its spirit or the scope of the appended claims.

What I claim as new and desire to secure by Letters Patent is:

1. In a drilling apparatus, in combination, a drill rotating motor, feeding means for said drill rotating motor comprising cooperating feeding elements, one of which is rotatable and the other continuously held against rotation, power means the source of operating energy for which is separate from said drill rotating motor for rotating said rotatable element, and means responsive to changes in resistance to rotation of said drill rotating motor for automatically controlling the rotation of said rotatable element.

2. In a drilling apparatus, in combination, a drill rotating motor, feeding means for said drill

rotating motor comprising cooperating feeding elements, one of which is rotatable and the other continuously held against rotation, said element continuously held against rotation being carried by said drill rotating motor for movement therewith, power means the source of operating energy for which is separate from said drill rotating motor for rotating said rotatable element, and means responsive to changes in resistance to rotation of said drill rotating motor and operative when the resistance exceeds a predetermined amount for automatically controlling the rotation of said rotatable element.

3. In a drilling apparatus, in combination, a drill rotating motor, supporting and guiding means for said motor, means for feeding said motor along said supporting and guiding means comprising cooperating feeding elements, of which one is rotatably mounted, respectively carried by said motor and said supporting and guiding means, and a feed motor for rotating said rotatable feeding element, and means responsive to changes in resistance to rotation of said drill rotating motor and operative when the resistance exceeds a predetermined amount for automatically increasing the resistance to rotation of said rotatable element.

4. In a drilling apparatus, in combination, a drill rotating motor, supporting and guiding means for said motor, means for feeding said motor along said supporting and guiding means comprising cooperating feeding elements, of which one is rotatably mounted, respectively carried by said motor and said supporting and guiding means, and means for controlling the rate of feed of said motor comprising brake disks rotating with said rotatable feeding element and movable longitudinally thereof, brake disks non-rotatably supported for movement with said motor along said supporting and guiding means and interleaved with said first mentioned brake disks, and means actuated by said motor on a predetermined increase in load on the latter for pressing said first and second mentioned brake disks into frictional engagement with each other.

5. In a drilling apparatus, in combination, a drill rotating motor, supporting and guiding means for said motor, means for feeding said motor along said supporting and guiding means comprising cooperating feeding elements, of which one is rotatably mounted, respectively carried by said motor and said supporting and guiding means, means for rotating said rotatable feeding element, and means for controlling the rate of feed of said motor comprising a friction element rotating with said rotatable feeding element and movable longitudinally thereof, a friction element non-rotatably supported for movement with said motor along said supporting and guiding means, and means actuated by said motor on a predetermined increase in load on the latter for pressing said friction elements together, thereby resisting rotation of said rotatable feeding element.

6. In a drilling apparatus, in combination, a rotary drilling motor for rotating a drill bit, supporting and guiding means for said motor, said motor being mounted on said supporting and guiding means for limited rotary movement relative thereto, means for feeding said motor along said supporting and guiding means comprising feeding elements, of which one is rotatably mounted, respectively carried by said motor and said supporting and guiding means, and means for controlling the rate of feed of said motor

75

comprising a friction element rotating with said rotatable feeding element and movable longitudinally thereof, a friction element non-rotatably supported for movement with said motor along said supporting and guiding means, and means for pressing said friction elements together including a member actuated by said motor on rotation of the latter relative to said supporting and guiding means.

7. In a drilling apparatus, in combination, a rotary drilling motor for rotating a drill bit, supporting and guiding means for said motor, said motor being mounted on said supporting and guiding means for limited rotary movement relative thereto, means for feeding said motor along said supporting and guiding means comprising feeding elements, of which one is rotatably mounted, respectively carried by said motor and said supporting and guiding means, and means for controlling the rate of feed of said motor comprising a friction element rotating with said rotatable feeding element and movable longitudinally thereof, a friction element non-rotatably supported for movement with said motor along said supporting and guiding means, and means for pressing said friction elements together including a member pivotally connected at one end to said motor supporting means and engaging one of said friction elements at its other end, and cam means fixed to said motor and operative on rotary movement of said motor relative to said supporting and guiding means due to overloading of the motor for swinging said pivoted member in a direction to engage said friction elements.

8. In a drilling apparatus, in combination, a rotary drilling motor for rotating a drill bit, supporting and guiding means for said motor, said motor being mounted on said supporting and guiding means for limited rotary movement relative thereto, feeding means for said drilling motor comprising feeding elements, of which one is rotatably mounted, respectively carried by said motor and said supporting and guiding means, said feeding elements effecting feeding of said drilling motor on relative rotation therebetween, means for rotating said rotatable element, and means including friction elements controlled by the rotary movement of said motor relative to said supporting and guiding means due to overloading of the motor for automatically controlling the rotation of said rotatable feeding element.

9. In a drilling apparatus, in combination, a drill rotating motor, feeding means for said drill rotating motor comprising cooperating feeding elements interengaged with each other and one of which is rotatable relative to the other to effect feed, a feed motor for rotating said rotatable element, and means controlled by the torque load changes on said drill rotating motor and operative when the torque load exceeds a predetermined amount for automatically increasing the resistance to rotation of said rotatable element.

10. In a drilling apparatus, a rotary drilling motor for rotating a drill bit, motor operated feeding mechanism for said drilling motor including elements operative on relative rotation to effect feed of said drilling motor, means for varying the resistance to rotation of certain of said elements and causing a variation in the relative rotation thereof, and means for actuating said last mentioned means automatically variably in proportion to excesses in torque above a predetermined amount exerted by said drilling motor.

11. In a drilling apparatus, in combination, a rotary drilling motor for rotating a drill bit, said rotary drilling motor having one of its elements connected in driving relation with a drill bit and another element, between which and the first a rotary reaction takes place when said motor is running, supported for limited rotary movement, feeding means for said motor including cooperating elements coacting on rotation of one of the same to effect motor feed, braking means for said last mentioned element, and operative connections between said second mentioned motor element and said braking means for actuating said braking means automatically when an excessive torque is exerted by said motor.

12. In a drilling apparatus, in combination, a drill rotating motor, feeding means for said drill rotating motor comprising cooperating feeding elements, of which one is rotatably mounted, means for rotating said rotatable feeding element to effect feed, means for resisting rotation of said rotatable element, and means responsive to the load changes on said drill rotating motor for controlling said resisting means to vary the resistance to rotation of said rotatable element, said last mentioned means being operative at predetermined load increases on said drill rotating motor for effecting a slowing down of said rotatable element to decrease the rate of feed.

13. In a drilling apparatus, in combination, a drilling motor for rotating a drill bit, feeding means for the drill bit including a rotatable feeding element, frictional resistance means for retarding the rotation of said rotatable feeding element, and means for automatically regulating said frictional resistance means to vary the rate of feed in accordance with variations in resistance to rotation of the drill bit.

14. In a drilling apparatus, in combination, a drilling motor for rotating a drill bit, feeding means for the drill bit including relatively rotatable, coacting feeding elements and a feeding motor for effecting relative rotation of said elements, said feeding motor constituting the sole source of power for said feeding means, and means automatically responsive to torque load changes on the drill bit for controlling the rate of relative rotation between said feeding elements to vary the rate of feed.

15. In a drilling apparatus, in combination, motor-operated means for rotating a drilling implement for causing the same to effect its drilling function, feeding means for the drilling implement comprising cooperating feeding elements, one of which is rotatable and the other continuously held against rotation, power means the source of operating energy for which is separate from said motor-operated means for rotating said rotatable feeding element to effect feed, and means responsive to changes in resistance to rotation of said implement-rotating-means for automatically controlling the rotation of said rotatable feeding element.

16. In a drilling apparatus, in combination, motor-operated means for rotating a drilling implement for causing the same to effect its drilling function, feeding means for the drilling implement comprising cooperating feeding elements, one of which is rotatable and the other continuously held against rotation, said element continuously held against rotation being mounted for movement with the drilling implement, power means the source of operating energy for which is separate from said motor-operated means for rotating said rotatable feeding element, and

means responsive to changes in resistance to rotation of said implement-rotating-means and operative when the resistance exceeds a predetermined amount for automatically controlling the rotation of said rotatable element.

17. In a drilling apparatus, in combination, motor-operated means for rotating a drilling implement for causing the same to effect its drilling function, supporting and guiding means for the drilling implement, means for feeding the drilling implement along said supporting and guiding means comprising cooperating feeding elements, of which one is rotatably mounted and the other is held against rotation, one feeding element adapted to move with the drilling implement and the other carried by said supporting and guiding means and relative to which the first is movable, said feeding means operative to effect feeding of the drilling implement on relative rotation of said feeding elements, and a feed motor for rotating said rotatable feeding element, and means responsive to changes in resistance to rotation of said implement-rotating-means and operative when the resistance exceeds a predetermined amount for automatically increasing the resistance to rotation of said rotatable feeding element.

18. In a drilling apparatus, in combination, motor-operated means for rotating a drilling implement for causing the same to effect its drilling function, feeding means for the drilling implement comprising cooperating feeding elements interengaged with each other and one of which is rotatable relative to the other to effect feed, and a feed motor for rotating said rotatable feeding element, and means controlled by the torque-load changes on said implement-rotating-means and operative when the torque load exceeds a predetermined amount for automatically increasing the resistance to rotation of said rotatable feeding element.

19. In a drilling apparatus, a motor for rotating a drilling implement, feeding mechanism for the drilling implement including elements operative on relative rotation to effect feed of the drilling implement and motor operated means for effecting relative rotation of said elements, means for varying the resistance to rotation of certain of said elements so as to vary the relative rotation thereof, and means for actuating said last mentioned means automatically variably in proportion to excesses in torque above a predetermined amount exerted by said implement-rotating-motor.

20. In a drilling apparatus, in combination, motor-operated means for rotating a drilling implement for causing the same to effect its drilling function, feeding means for a drilling implement comprising cooperating feeding elements, of which one is rotatably mounted, means for rotating said rotatable feeding element to effect feed, and means responsive to the torque-load changes on said implement-rotating-means for varying the resistance to rotation of said rotatable feeding element, said last mentioned means being operative at predetermined torque-load increases on said implement-rotating-means for effecting a slowing down of said rotatable feeding element to decrease the rate of feed.

21. In a drilling apparatus, the combination comprising motor operated means for rotating a drilling implement, feeding means for the drilling implement including a torque motor adapted to exert a substantially constant feeding force, and means responsive to torque-load changes on said

13

implement-rotating-means for automatically controlling the transmission of the feeding forces from said torque motor to the drilling implement to regulate the rate of feed.

22. In a drilling apparatus, the combination comprising motor operated means for rotating a drilling implement, means for feeding the drilling implement including relatively rotatable mechanically interengaged feeding elements, and braking means responsive to torque load changes on said implement-rotating-means for automatically controlling the rate of relative rotation of said feeding elements to regulate the rate of feed.

23. In a drilling apparatus, the combination comprising motor operated means for rotating a drilling implement, means for feeding the drilling implement including a torque motor adapted to exert a substantially constant feeding torque, frictional means for resisting the operation of said torque motor, and means responsive to torque-load changes on said implement-rotating-means for automatically controlling the loading of said frictional resistance means to regulate the rate of feed.

24. In a drilling apparatus, the combination comprising motor operated means for actuating

14

a drilling implement, means for feeding the drilling implement including relatively rotatable mechanically interengaged feeding elements, frictional resistance means operatively connected to one of said elements for controlling the rotation thereof, and means responsive to load changes on said implement-actuating-means for automatically controlling the loading of said frictional resistance means to regulate the rate of feed.
